UNITED STATES PATENT OFFICE.

LUSTER F. HARRIS AND WALTER L. WILLIAMS, OF CLEBURNE, TEXAS.

INCUBATOR-REGULATOR.

1,253,593.

Specification of Letters Patent. Patented Jan. 15, 1918.

Application filed July 25, 1916. Serial No. 111,267.

To all whom it may concern:

Be it known that we, LUSTER F. HARRIS and WALTER L. WILLIAMS, citizens of the United States, residing at Cleburne, in the county of Johnson, State of Texas, have invented certain new and useful Improvements in Incubator-Regulators; and we do hereby declare the following to be a full, clear, and exact description of the invention, such as will enable others skilled in the art to which it appertains to make and use the same.

This invention relates to incubators and has special reference to an automatic regulator for the flame of an incubator or other heating lamp.

One important object of the invention is to provide an improved and simplified construction of devices of this character.

A second important object of the invention is to provide an improved regulator arranged to raise or lower the wick of an incubator lamp in accordance with the heat in the incubator itself, the wick being lowered when the heat is excessive, and raised when the heat diminishes below a certain point.

A third important object of the invention is to provide a device of this character of improved construction arranged to permit regulation of the flame independently of the heat controlled member of the device.

A fourth important object of the invention is to provide an improved general construction of incubator for use in connection with this regulator.

With the above and other objects in view, as will be hereinafter apparent the invention consists in general of certain novel details of construction and combinations of parts hereinafter fully described, illustrated in the accompanying drawings, and specifically claimed.

In the accompanying drawings, like characters of reference indicate like parts in the several views, and:

Figure 1 is a front view of the incubator with the door raised.

Fig. 2 is a section on the line 2—2 of Fig. 1.

Fig. 3 is a section on the line 3—3 of Fig. 2.

Fig. 4 is a section on the line 4—4 of Fig. 1.

Fig. 5 is a detail section on the line 5—5 of Fig. 4. 55

Fig. 6 is a detail section on the line 6—6 of Fig. 1.

In the embodiment of the invention herein illustrated there is disclosed an incubator 60 having a casing 10 provided with front and rear doors 11 and 12 respectively. This casing 10 is preferably supported on legs 13 and extending up through the center of the casing is a chimney 14 having openings 15 65 just above the floor of the casing so that the heated air and products of combustion may pass out of these openings into such casing. Mounted on the top of the casing 10 is a bracket 16 whereto is hinged an arm 17 which extends over the top of the chimney 14 and is provided with a circular damper 18, the hinge connection permitting the damper to be raised or lowered with respect to the top of the chimney 14. In order 70 to hold the arm 17 in adjusted position there is provided a thumb-screw 19 which passes through the arm and bears against the top of the casing. Thus, when the thumb-screw is screwed down the arm 17 will be lifted 80 and the damper 18 raised, while, when the thumb-screw is screwed in a reverse direction the arm 17 will be permitted to fall and consequently the damper 18 will be moved 85 else to the top of the chimney 18. By this means the quantity of the heated air and products of combustion that escape through the openings 15 may be regulated.

Beneath the casing 10 there is provided a lamp having a body 20 and burner 21. 90 This lamp is connected to the chimney 14 by a chimney 22 preferably of metal with a sight opening in one side covered by mica or other like materials. This burner 21 is provided with a wick raising and lowering 95 shaft 23 having the usual thumb-nut 24 on one end.

Mounted within the casing 10 is a bracket 25 whereto is fixed an expansion member 26 here shown as consisting of the usual mercury expansion cell. Secured to one end of the bracket 25 is a depending bracket 27 and pivoted to this depending bracket 27 is an arm 28 against which a stem 29 on the cell 26 bears so that as the cell expands the 100 arm 28 will be forced downward. Connected to the free end of this arm 28 is one end of a spring 30, the other end of said spring 105

being connected to the bracket 25 so that as the cell 26 contracts the spring 30 will cause the arm 28 to raise. Pivoted to the arm 28 adjacent the free end thereof is a rod 31 and this rod extends down through the bottom of the casing 10. Mounted on the rod 31 is a sleeve 32 which is slidable on said rod and is held in adjusted position by means of a thumb-screw 33. Fixedly connected to the sleeve 32 is a link 34 which has a bifurcated lower end as clearly shown in the drawings.

On the bottom of the casing 10 is a bracket 35 fixed to which is a parallel bearing member 36 and through this bracket 15 and the bearing member 36 extends a shaft 37 which forms a continuation of the shaft 23, being braced or otherwise fixedly secured thereto. Fixed upon this shaft 37 between the bracket 35 and the member 36 is a pinion 20 38. Extending between the bracket 35 and the member 36 is a second shaft 39 and on this second shaft is pivoted a segmental gear 40 which meshes with the pinion 38 so that as the gear is rotated about its pivot shaft 39 the pinion 38 will be rotated and the lamp wick raised or lowered in accordance with the direction of movement of such gear 40. The forked lower end of the link 34 straddles the upper part of the gear 40 and 30 is pivoted thereto.

In the operation of the device, if the heat in the incubator becomes greater than that desired the expansion of the member 26 will cause depression of the arm 28 and this in turn will act upon the rod 31 to move said rod downward. The sleeve 32, being locked to the rod 31, by the thumb-screw 33 will force the link 34 downward and this in turn will move the segmental gear 40 downward so that the pinion 38 and shaft 23 will rotate in a direction which will lower the lamp wick. If the temperature in the incubator becomes too cool the expansion member 26 will contract and this will permit the spring 30 to raise the arm 28 and the reverse of the foregoing operation will take place, the wick being raised. It will be observed that the sleeve 32 may be released from the rod 31 and moved up and down independently of the movement of said rod so that the height of the wick may be adjusted to start with before tightening the set screw 33 to cause automatic regulation of such wick. By means of this arrangement the wick may be trimmed at any time desired and then brought back roughly to the proper height and the sleeve 32 locked in position. The automatic regulator will then take care of the balance of the adjustment so that it will be unnecessary to adjust the wick at the exact temperature desired.

There has thus been provided a simple and efficient device of the kind described and for the purpose specified.

It is obvious that many minor changes 65 may be made in the form and construction of the invention without departing from the material principles thereof. It is not therefore desired to confine the invention to the exact form herein shown and described but 70 it is wished to include all such as properly come within the scope claimed.

Having thus described the invention, what is claimed as new, is:

1. In combination with a heated chamber 75 and its lamp, a regulator for said lamp comprising a bracket depending from said heated chamber, and forming a bearing for one end of a wick raising shaft, a gear fixedly secured to the wick raising shaft, a frame 80 supported by said bracket, one end of which forms a shaft, a segmental gear mounted on said last mentioned shaft and meshing with the gear on the wick raising shaft, a thermal expansion member arranged within the heat chamber, a pivoted member engaging the thermal expansion member, resilient means connecting the free end of the pivoted member with one of the walls of the heat chamber, and means connecting the pivoted member, with the segmental gear member for operating the wick raising shaft upon operation of the thermal expansion member.

2. In combination with a heated chamber and its lamp, a regulator for said lamp comprising a bracket depending from said heated chamber, and forming a bearing for one end of a wick raising shaft, a gear fixedly secured to the wick raising shaft, a frame 95 supported by said bracket, one end of which forms a shaft, a segmental gear mounted on said last mentioned shaft and meshing with the gear on the wick raising shaft, a thermal expansion member arranged within the heat chamber, a pivoted member engaging the thermal expansion member, resilient means connecting the free end of the pivoted member with one of the walls of the heat chamber, and adjustable means pivotally secured at one end to the pivoted member, and 100 pivotally secured at its other end to said segmental gear for operating the wick raising shaft upon movement of the thermal expansion member.

In testimony whereof, we affix our signatures, in the presence of two witnesses:

LUSTER F. HARRIS.
WALTER L. WILLIAMS.
